HYDROCARBON CONVERSION PROCESS
Harry M. Brennan, Hammond, Ind., and Marvin J. Den
Herder, Olympia Fields, Ill., assignors to Standard Oil
Company, Chicago, Ill., a corporation of Indiana
Filed July 20, 1964, Ser. No. 383,650
15 Claims. (Cl. 208—110)

This invention relates to a hydrocarbon conversion process and more particularly it relates to an improved method of hydrocracking a relatively high-boiling hydrocarbon feedstock to produce lower-boiling hydrocarbons boiling predominantly within the gasoline boiling range. This application is a continuation-in-part of S.N. 134,030, now abandoned.

As is well known to those skilled in the art, hydrocracking is a general term applied to refining processes wherein hydrocarbon feedstocks of relatively high molecular weight are converted to mixtures of hydrocarbons of lower molecular weights, and wherein the conversion is carried out at elevated temperature and pressure in the presence of a hydrogen-affording gas. In the hydrocracking operation, it is, of course, desirable to increase the efficiency of the process, and one of the main objects is to obtain the maximum conversion of the high molecular weight feed to lower boiling materials, and at the same time provide a product having the desired characteristics. In hydrocracking, typically, hydrocarbon feeds such as catalytic cycle oils and gas oils boiling in the range of about 350° F. to 1,000° F. are hydrocracked to obtain gasoline-boiling-range products and light distillates.

It has been discovered that the operation of a hydrocracking process can be improved by carrying out the conversion in the presence of a small amount of light olefin hydrocarbons, e.g., C₃ to C₈ olefins, and preferably, C₅ to C₈ olefins. According to the concept of the present invention, a relatively high boiling hydrocarbon feed is contacted with a hydrocracking catalyst in the presence of hydrogen, or a hydrogen-affording gas, under hydrocracking conditions and in the presence of about 0.3 to 20 mole percent of light olefins, based on feed, to increase the hydrocracking reaction rate without adversely affecting the product distribution. A concentration of 0.3 to 6 mole percent of light olefins is advantageous; a concentration of 1.5 to 4 mole percent is preferred.

In a preferred embodiment of the invention a light olefinic hydrocarbon such as a light catalytically cracked naphtha rich in C₅—C₆ olefins of a C₅ fraction thereof is added to the feedstock prior to its introduction into the hydrocracking zone to provide between 1.5 and 4 mole percent light olefin, based on feed, during the conversion. The hydrocracking process preferably is one employing a Group VIII metal hydrogenation component and a solid acidic cracking component wherein the catalyst activities are balanced to provide a high iso to normal ratio in the paraffins produced; and the hydrocracking conditions advantageously include a temperature between about 450° F. and 750° F., optimally, 500° F.—700° F.; and a pressure between about 200 and 2,000 p.s.i.g., optimally, 750—1,000 p.s.i.g. Advantageously, a catalytically cracked cycle oil containing a substantial concentration of polynuclear aromatics is employed as feed to the hydrocracker.

The present method has been found to increase the rate of the hydrocracking conversion without adversely affecting the product distribution. This enables the refiner to employ processing equipment of a smaller size; and/or to employ less severe hydrocracking conditions; and/or requires a smaller catalyst charge. Further, light normal olefins which are introduced into the hydrocracking zone and similar hydrocarbons formed during the conversion

2

are converted to saturated, branched hydrocarbons, and the iso to normal paraffin ratio is greater than the thermodynamic equilibrium ratio. The isoparaffins formed are additional high octane gasoline components. It is believed that the olefins introduced into the hydrocracking zone form carbonium ions which occupy catalyst sites so as to promote the hydrocracking reaction, while at the same time the olefins undergo hydrogenation and/or isomerization and are converted to isoparaffins.

10 The advantages of the invention are obtained to the fullest extent by injecting the light olefins to the hydrocracking reaction zone in a stagewise manner. In fixed bed or other systems where the reactants flow through the reaction zone, olefins injected with the feed tend to be 15 hydrogenated relatively rapidly and their valuable promotional effect dissipated. Thus, stepwise injection of the light olefins provides beneficial results. Moreover, it has been found that when an amount of light olefin exceeding upwards of about 6 mole percent is added, the advantage 20 of increased conversion deriving from the invention is lost and, as the proportion of olefins is increased, conversion tends to be decreased. Since, however, it is often advantageous in refinery operation to maximize utilization of light olefins, multiple injection of the light olefins 25 within the limits contemplated by the invention is most beneficial.

The number of injection points and, consequently, the total amount of olefin injected, can vary according to the dimensions of the reaction vessel employed. Likewise, 30 the injection points may be aligned longitudinally along the vessel, or they may be located at various points at the circumference.

The invention will be better understood by reference to the following description and accompanying drawing 35 which is illustrative of a preferred hydrocracking scheme.

In the operation of the process, a selected feedstock is introduced into a reaction zone containing catalyst along with a hydrogen-affording gas such as hydrogen gas, catalytic reformer make-gas or a recycled hydrogen-rich gas 40 from the present process. The process may be operated in the liquid phase, the vapor phase or mixed vapor-liquid phase. The catalyst system may be of the fixed-bed type, as well as a fluidized bed or other appropriate type of system. The feedstocks employed may be derived from petroleum, shale, gilsonite or other such sources.

The feedstocks which may be satisfactorily hydrocracked in the present process may have compositions ranging from essentially all saturates to all aromatics. Saturates are hydrocracked to gasoline-boiling-range 50 paraffins containing a greater than equilibrium concentration of isoparaffins in the product, while in the case of polynuclear aromatics these are partially hydrogenated and the hydrogenated ring portion is hydrocracked to afford an alkyl substituted benzene and an isoparaffin.

High boiling fractions of crude oil which boil up to about 1200° F. may constitute advantageous feedstocks for the process of the invention. Most generally the feedstock will range from naphtha and kerosene through 60 the light and heavy gas oils. The feedstock will normally boil between about 300° F. and 1,000° F. Advantageously, the boiling range of the feedstock is about 300° F. to about 850° F. Examples of desirable feedstocks are light catalytic cycle oil having a boiling range of from about 350° F. to 650° F., heavy catalytic cycle oil boiling in the range of about 500° F. to 850° F., virgin gas oil boiling from about 400° F. to 1,000° F. and coker gas oil boiling in the range of about 350° F. to 800° F.

70 Product yields are especially dependent upon the nature of the feedstock, the process conditions and the catalyst employed in the process. In each instance it is necessary

to correlate the aforementioned factors according to the desired product.

Normal amounts of sulfur which are found in the above-described feedstocks do not adversely affect the catalyst employed in the present invention. Desirably, nitrogen and oxygen as components of compounds in the feedstock are kept as low as possible in order to maintain a desirably long cycle life, i.e., the period of time for which the catalyst remains effective in producing the desired product. With higher nitrogen contents in the feedstock more frequent regenerations are required to maintain a suitable cycle life. The feed may contain up to about 0.1 weight percent nitrogen, but preferably is less than about 0.001 weight percent nitrogen in order to maintain a more satisfactory cycle life.

Since a number of refining streams suitable as hydrocracking feeds contain considerable amounts of nitrogen, it is highly desirable to pretreat such streams to reduce the nitrogen content thereof. Hydrogen treating processes, such as that wherein the feed is contacted with a cobalt-molybdena-on-alumina catalyst in the presence of hydrogen at elevated temperatures and pressure, are suitable for pretreating the feed.

The light olefinic hydrocarbons employed in the invention, typically, may be selected from the available light cracked gasolines and naphtha which contain light olefins in substantial amounts. Advantageously, catalytic naphtha, containing about 50 percent C₄-C₇ olefins, coker gasoline containing C₄-C₁₁ hydrocarbons and substantial light olefins, or fractions of such streams can be employed as the source of light olefins. As noted above, the conversion is carried out in the presence of about 0.3 to 6 mole percent, preferably about 1.5 to 4 mole percent, of the light olefins.

The process conditions which are employed in the present invention can be selected over a relatively wide range and are correlated, according to the nature of the feedstock and of the particular catalyst employed, so as to produce either a desired conversion; i.e., as the percentage of feedstock converted to product, or a product of a desired octane number. The formation of alkylbenzenes from polynuclear aromatics is favored by higher pressures and moderate temperatures, and an increase in both of these variables has the effect of increasing the degree of conversion. Satisfactory conversions are obtained with the above described feedstocks at pressures in the range of about 200 and 2,000 p.s.i.g., and temperatures in the range of about 400° F. to 1,000° F., although pressures and temperatures outside of these ranges may be employed when utilizing certain feedstocks, particularly highly refractory feeds. Advantageously, pressures in the range of about 750 to 1,500 p.s.i.g., and temperatures between about 500° F. to 700° F. are employed. It may be desirable during the course of a run to increase the temperature within the reaction zone as the catalyst deactivates in order to compensate for a drop in catalyst activity. Thus, with a fresh or newly regenerated catalyst it may be desirable to come on stream at a temperature of about 500° F. and to gradually increase the operating temperature towards about 700° F. during the course of a run. In most instances it is desirable to maintain a low operating temperature, since higher temperatures have been found to result in increased coking and increased amounts of gas formation.

The space velocity, expressed herein as liquid hourly space velocity (LHSV), in terms of volumes of oil charged to the reaction zone per hour per volume of catalyst, may range from about 0.1 to 10, normally from about 0.2 to 5, and preferably from about 0.25 and 2 LHSV. Lower space velocities tend to increase the degree of conversion.

Hydrogen is consumed in the process and it is necessary to maintain an excess of hydrogen in the reaction zone. However, the process is relatively unaffected by changes in the hydrogen-to-oil ratio within the general range of

operations. The hydrogen-to-oil ratio employed, desirably, is in the range of about 1,000 to 10,000 standard cubic feet of hydrogen gas per barrel of feed (s.c.f.b.) and advantageously about 2,000 to 5,000 s.c.f.b. is employed.

With a light catalytically cracked cycle oil as feed, it has been found that over wide ranges of operating conditions the products of the hydrocracking process predominantly boil within the gasoline boiling range. The dry gas make; i.e., methane through propane, generally is less than about 5 weight percent and, typically, is in the order of about 2 to 3 weight percent. Typically, the butane-pentane fraction of the product also is about 15 to 30 weight percent, with the amount produced being more dependent upon operating conditions and the nature of the feedstock. When employing a feedstock such as light catalytic cycle oil the pentane-plus to 400° F. fraction of the product generally will range upwardly from about 70 weight percent of the total converted product.

Typically, when it is desired to maximize the production of light distillates, i.e., materials boiling above the gasoline range and having an endpoint of about 550-600° F. a heavy catalytic cycle oil boiling above about 600° F. is utilized as feed. The hydrocrackate is fractionated to provide a heavy bottoms fraction boiling above about 600° F. which is recycled to the hydrocracking zone. The amount of heavy hydrocarbons converted to distillates can be further increased by decreasing the conversion per pass.

The catalyst employed in the present process may be selected from the various well known hydrocracking catalysts, which typically comprise a hydrogenation component, which possesses hydrogenation-dehydrogenation activity and may exist in the form of certain hereinafter-specified metals or the oxides or sulfides thereof, and a solid acidic cracking component. Preferably, the hydrocracking catalyst further comprises an activity control-affording material which effectively balances the catalyst activities to provide a low rate of hydrogenation relative to the isomerization occurring during the over-all conversion. Such catalysts having balanced activities have been found to be capable of providing a product of suitable characteristics, such as more highly branched paraffins and better product distribution. These activity control-affording elements are normally employed in relatively small amounts, depending upon the activity of the hydrogenation component relative to that of the acidic component, and are further described hereinbelow.

The acidic cracking component of the catalyst may comprise one or more solid acidic components such as silica-alumina (naturally occurring and/or synthetic) silica-magnesia, silica-alumina-zirconia, and the like. Also, acid-treated-aluminas, with or without halogens, such as fluorided alumina, boria-alumina, and the heteropolyacid-treated aluminas, i.e., treated with phosphotungstic acid, phosphovanadic acid, silicotungstic acid, silicomolybdovanadic acid and the like, may be employed. However, it is critical that such materials possess substantial cracking activity in the finished catalyst composite.

A preferred acidic component of the present catalyst composition is one of the commercially available synthetic silica-alumina cracking catalysts which may contain about 5 to 40 weight percent alumina. Preferably, the acidic component of the catalyst is employed as a support and it is highly porous, having a surface area of between about 100 and 500 square meters per gram. The preparation and properties of the acidic cracking components are well-known in the art and they need not be described further herein for the purpose of the present invention.

For example, see the series entitled "Catalysis" by Emmett (Reinhold Publishing Corporation), particularly volume VII, pp. 1-91.

Many of the well-known metallic hydrogenation catalysts may be incorporated in the present catalyst, but preferably, the metallic constituent of this component is selected

from the metals of Group VIII of the Periodic Table which are known to possess satisfactory hydrogenation activities, especially nickel, platinum, cobalt and palladium, or from the metals of Group VI, especially tungsten molybdenum. The hydrogenation component of the catalyst advantageously can be incorporated into the catalyst by impregnating a porous acidic cracking component with a heat-decomposable compound of the hydrogenation metal, followed by calcining to provide a composite. Typically, a silica-alumina cracking catalyst or an acid-treated alumina base is impregnated with a solution of nickel acetate, chloroplatinic acid or the like, and then dried; followed by pelleting and calcining at an elevated temperature (about 1,000° F.).

However, it is contemplated that the finished catalyst may also be produced by various methods such as by cogelling the various components and by other well-known variations in catalyst preparation techniques to produce a finished catalyst having the desired properties.

The amount of the hydrogenation component incorporated in the catalyst can vary over a wide range, with the amount being selected to provide the desired catalyst activity. For example, large amounts of nickel, e.g., up to about 30 weight percent can be employed, and relatively small amounts of nickel, e.g., as little as about 0.1 weight percent is also effective with about 0.5 to 5 weight percent nickel being preferred. Typically, about 0.1 to 2 weight percent platinum is effective in the catalyst and preferably about 0.1 to 1 weight percent platinum is employed. The amount of the hydrogenation component employed in the catalyst thus will depend upon the catalytic ability and economic factors.

Elements which have been found to be capable of providing and advantageous balance in activities between the metallic hydrogenation component and the solid acidic component include the normally solid elements of Group VIA of the Periodic Table, especially sulfur; the normally solid elements of Group VA of the Periodic Table, especially arsenic and antimony; and metals such as lead, mercury, copper, zinc, cadmium and the like, especially lead, mercury and copper. These catalyst modifying elements typically are incorporated into the catalyst during the catalyst manufacture by impregnating a composite such as nickel on silica-alumina with a solution of an organic or inorganic compound, such as triphenyl arsine, arsenic trioxide, triphenyl stibine, lead nitrate, or mercuric nitrate, and/or by treating with sulfur compounds, such as carbon disulfide and hydrogen sulfide, which may be present in the feed or in the hydrogen. Where the composite is impregnated with a liquid solution such as organo-metallic compound of the desired element, the liquid is evaporated to leave a deposit on the base and the impregnated deposit is then treated with hydrogen at an elevated temperature, typically about 850° F., to reduce the catalyst. However, it is also contemplated that the above elements may be introduced into the reaction zone during the on-oil period or during the other processing periods such as during the regeneration to contact the catalyst base in situ and thereby incorporate the element into the catalyst. As mentioned above only small amounts of activity control-affording elements are generally required in the catalyst. Typically about 0.1 to 5 moles of arsenic or antimony, preferably 0.1 to 1 mole and optimally 0.25 to 0.75 mole of these elements per mole of the hydrogenation metal is employed. Likewise, about 0.03 to 5, optimally about 0.05 to 2 and preferably about 0.1 to 1 mole of the metals such as copper, lead or mercury per mole of the hydrogenation metal is incorporated into the catalyst.

Among the benefits obtained from employing the above-mentioned balanced catalysts in the present process are the increased production of branched chain paraffins, more favorable control of catalyst activity and the simplification of catalyst reactivation techniques whereby a

readily regenerable catalyst can be employed in the process.

Turning now to the drawing, a hydrocracking feedstock such as a heavy catalytic cycle oil boiling in the range of about 550° F.-650° F. and containing substantial amounts of polycyclic aromatic hydrocarbons is passed by way of line 11 into a hydrocracking reactor 12 containing a bed of arsenided nickel on silica-alumina catalyst. The catalyst contains 5 percent nickel, 2.5 percent arsenic and the silica-alumina support contains about 25 percent Al_2O_3 . Hydrogen from line 13 is commingled with the feedstock and introduced into the reactor. Make-up hydrogen may be introduced into the system by way of line 13a. A catalytic debutanized naphtha having an ASTM distillation initial boiling point of 78° F. and an endpoint of 339° F., containing 8.8 weight percent C_4 's 34.4 weight percent C_5 's 28.1 weight percent C_6 's and 17.1 weight percent C_7 's and containing 53.5 percent olefins is introduced into the reactor through line 14. Typically, about 3 weight percent naphtha, based on total feed (about 4.4 mole percent olefins) is introduced into the reactor commingled with the feed. Conditions within the hydrocracking reactor 12 include a temperature in the range of about 500° F.-700° F., a pressure in the range of 750 to 1,500 p.s.i.g., an overall liquid hourly space velocity between about 0.5 and 5 volumes of hydrocarbon per hour per volume of catalyst. The effluent is withdrawn from the reactor 12 via line 18, cooled by passing through a heat exchanger 19 and passed by way of line 21 into a high pressure separator 22 wherein a hydrogen-rich gas is separated from the liquid hydrocrackate and passed by way of line 23 to line 13 to be recycled to the hydrocracking zone in the reactor. The hydrogen-to-hydrocarbon ratio within the reaction zone is between about 1,000 and 10,000 standard cubic feed of hydrogen per barrel of hydrocarbon. The remaining liquid hydrocrackate is then passed by way of line 24 to a separation means, such as fractionator 26, wherein it is distilled to separate out a light gaseous overhead fraction containing predominantly C_1 through C_4 hydrocarbons, a light isoparaffin-rich hydrocrackate fraction boiling in the range of C_5 to 180° F. and a heavy aromatics-rich hydrocrackate fraction boiling in the range of about 180° F. and 400° F. A bottoms fraction boiling above 400° F. is withdrawn via line 27 and is recycled to the hydrocracking zone by way of line 28.

The present invention will be better understood by reference to the following examples, which illustrate the beneficial effects on the operation of a hydrocracking process obtained by the addition of small amounts of light olefins to the hydrocracking reaction zone. It is to be understood that the following examples which are given for the purpose of illustration only do not serve in any way to limit the scope of the present invention.

EXAMPLE 1

A catalyst was prepared which comprised 5 weight percent nickel and 2.5 weight percent arsenic on a silica-alumina support containing about 25 weight percent alumina. In preparing the catalyst, a commercially high alumina silica-alumina cracking catalyst was impregnated with an aqueous solution of nickel acetate. The impregnated composite was dried at about 400° F., and calcined at 1,000° F. The calcined catalyst was then impregnated with a solution of triphenyl arsine in normal heptane. The heptane was evaporated and the arsenic treated catalyst was reduced in flowing hydrogen at atmospheric pressure and about 850° F.

A light catalytic cycle oil (LCCO) was hydrodesulfurized over a cobalt-molybdena catalyst to reduce the sulfur and nitrogen to 3 p.p.m. and 9 p.p.m. respectively. The estimated molecular weight of the cycle oil was about 200.

The hydrogen-treated cycle oil, together with varying amounts of pentane-2, was hydrocracked by contacting

the hydrocarbons with the arsenided-nickel-on-silica-alumina catalyst in a reactor at 550° F., 1000 p.s.i.g., a liquid hourly space velocity of 0.5 volume of hydrocarbon per hour per volume of catalyst. Hydrogen gas was supplied to the reactor to provide a hydrogen-to-hydrocarbon ratio of 6,350 standard cubic feet of hydrogen per barrel of hydrocarbon. The results obtained from the addition of the varying amounts of olefins to the hydrocracking feedstock are shown below in Table I wherein the product analysis and percentage conversion of the feedstock are given. Also indicated are the iso to normal (*i/n*) paraffin ratios for the butane and pentane fractions of the reactor effluent.

Table I

Example No.	Wt. Percent Olefin Based on LCCO	Approx. Mole Percent Based on LCCO	<i>i/n</i> Ratio		Weight Percent Yields				Percent LCCO Converted
			C ₄	C ₅	C ₁ -C ₃	C ₄	C ₅ -180	180-400	
1-----	0.0	0.0	3.3	6.7	2.9	8.0	2.7	28.5	57.5
2-----	0.45	1.3	2.0	12.3	1.7	6.6	7.5	37.8	46.2
3-----	0.90	2.6	1.5	8.8	1.6	5.8	8.2	40.0	44.3
4-----	1.35	4.0	1.4	8.9	2.0	4.9	10.3	41.0	41.0
5-----	1.80	5.7	1.6	6.5	1.3	5.7	6.9	35.7	49.8

EXAMPLE 2

A sulfided nickel on silica-alumina catalyst was prepared by impregnating a silica-alumina cracking catalyst (25 percent alumina) with an aqueous solution of nickel acetate. The impregnated composite was dried and calcined as described above. The final composite contained 5 weight percent nickel. Subsequently, the nickel on silica-alumina composite was sulfided by contacting it with a mixture of 92 percent hydrogen and 8 percent hydrogen sulfide at atmospheric pressure and a temperature of 750° F. A cetane feed containing 0.5 weight percent sulfur as carbon disulfide was contacted with the sulfided nickel on silica-alumina catalyst under the same conditions as described above. Varying amounts of pentane-2 were added to the feed and the results of the olefin addition are shown below in Table II.

Table II

Example No.	Wt. Percent Olefin Based on C ₁₆	Approx. Mole Percent Olefin Based on C ₁₆	C ₅ <i>i/n</i> Ratio	Weight Percent Yields					Percent Conversion of Reactant
				C ₁ -C ₃	C ₄	C ₅ -180	180-400	400+	
6-----	0.0	0.0	15.1	4.0	18.8	27.0	18.2	31.4	68.5
7-----	0.5	1.8	14.0	5.0	26.2	30.7	18.7	18.1	80.5
8-----	10.0	36.0	11.3	3.6	13.9	27.7	16.8	37.2	58.7

From the above examples it is seen that small amounts of light olefins added to the hydrocracking feed resulted in a surprising increase in the degree of conversion of the high boiling feed to lower boiling hydrocarbons. It is further seen that if the olefins are present in excess amounts the conversion level is not increased and in fact, may even be lowered.

From the foregoing description of the present invention various modifications in the details of the operation of the hydrocracking process will become apparent to the skilled artisan, which modifications fall within the spirit and scope of the present invention.

What is claimed is:

1. A hydrocracking process which comprises adding an olefinic hydrocarbon having from 4 to 7 hydrocarbons per molecule to a high-boiling hydrocarbon feedstock to provide said olefinic hydrocarbon in an amount in the range of from about 0.3 to 6 mole percent, based on feed, and

contacting the mixture of said olefinic hydrocarbon and said feedstock in a hydrocracking reaction zone with a hydrocracking catalyst, in the presence of a hydrogen-
affording gas at a temperature in the range of about 400°
5 F. to about 1000° F. and a pressure in the range of about
200 to about 2,000 p.s.i.g., said catalyst comprising a
metallic hydrogenation component containing a metal
selected from the hydrogenation metals of Group VI and
Group VIII of the Periodic Table and a solid acidic crack-
ing component, the activities of said hydrogenation com-
ponent and of said cracking component being balanced
to provide a high iso-to-normal ratio in the paraffins pro-
duced.

2. The process of claim 1 wherein said catalyst further comprises a minor amount of an activity-control-affording element effective to control the activities of said hydro-
genation component and said acidic component to pro-
vide a high iso-to-normal ratio in the paraffins produced.

3. A hydrocracking process which comprises adding an
olefinic hydrocarbon having from 4 to 7 carbon atoms
35 per molecule to a hydrocarbon feedstock boiling in the
range of about 350° F. to about 850° F. to provide said
olefinic hydrocarbon in an amount in the range of about
0.3 to 6 mole percent, based on feed, and contacting the
mixture of said olefinic hydrocarbon and said feedstock
40 in a hydrocracking reaction zone with a hydrocracking
catalyst in the presence of a hydrogen-affording gas at a
temperature in the range of about 450° F. to about 750°
F., a pressure in the range of about 200 to 2,000 p.s.i.g.,

60 a liquid hourly space velocity in the range of about 0.1
to 10 volumes of hydrocarbon per hour per volume of
catalyst and a hydrogen-to-hydrocarbon ratio in the range
of about 1,000 to 10,000 standard cubic feet of hydro-
gen per barrel of hydrocarbon, said catalyst comprising
(a) a solid acidic support having substantial cracking
activity, and (b) a metallic hydrogenation component
65 comprising a metal selected from the group consisting
of the hydrogenation metals of Group VI and Group
VIII of the Periodic Table and a minor amount, effective
to provide a high iso-to-normal ratio in the paraffins pro-
duced, of an activity-control-affording element selected
70 from the group consisting of sulfur, lead, mercury, copper,
arsenic and antimony.

4. The process of claim 3 wherein said olefinic hydro-
carbon is added to said feedstock prior to its introduction
into said reaction zone.

75 5. The process of claim 1 wherein the addition of said

from the metals of Group VIII of the Periodic Table which are known to possess satisfactory hydrogenation activities, especially nickel, platinum, cobalt and palladium, or from the metals of Group VI, especially tungsten molybdenum. The hydrogenation component of the catalyst advantageously can be incorporated into the catalyst by impregnating a porous acidic cracking component with a heat-decomposable compound of the hydrogenation metal, followed by calcining to provide a composite. Typically, a silica-alumina cracking catalyst or an acid-treated alumina base is impregnated with a solution of nickel acetate, chloroplatinic acid or the like, and then dried; followed by pelletizing and calcining at an elevated temperature (about 1,000° F.).

However, it is contemplated that the finished catalyst may also be produced by various methods such as by cogelling the various components and by other well-known variations in catalyst preparation techniques to produce a finished catalyst having the desired properties.

The amount of the hydrogenation component incorporated in the catalyst can vary over a wide range, with the amount being selected to provide the desired catalyst activity. For example, large amounts of nickel, e.g., up to about 30 weight percent can be employed, and relatively small amounts of nickel, e.g., as little as about 0.1 weight percent is also effective with about 0.5 to 5 weight percent nickel being preferred. Typically, about 0.1 to 2 weight percent platinum is effective in the catalyst and preferably about 0.1 to 1 weight percent platinum is employed. The amount of the hydrogenation component employed in the catalyst thus will depend upon the catalytic ability and economic factors.

Elements which have been found to be capable of providing and advantageous balance in activities between the metallic hydrogenation component and the solid acidic component include the normally solid elements of Group VIA of the Periodic Table, especially sulfur; the normally solid elements of Group VA of the Periodic Table, especially arsenic and antimony; and metals such as lead, mercury, copper, zinc, cadmium and the like, especially lead, mercury and copper. These catalyst modifying elements typically are incorporated into the catalyst during the catalyst manufacture by impregnating a composite such as nickel on silica-alumina with a solution of an organic or inorganic compound, such as triphenyl arsine, arsenic trioxide, triphenyl stibine, lead nitrate, or mercuric nitrate, and/or by treating with sulfur compounds, such as carbon disulfide and hydrogen sulfide, which may be present in the feed or in the hydrogen. Where the composite is impregnated with a liquid solution such as organo-metallic compound of the desired element, the liquid is evaporated to leave a deposit on the base and the impregnated deposit is then treated with hydrogen at an elevated temperature, typically about 850° F., to reduce the catalyst. However, it is also contemplated that the above elements may be introduced into the reaction zone during the on-oil period or during the other processing periods such as during the regeneration to contact the catalyst base in situ and thereby incorporate the element into the catalyst. As mentioned above only small amounts of activity control-affording elements are generally required in the catalyst. Typically about 0.1 to 5 moles of arsenic or antimony, preferably 0.1 to 1 mole and optimally 0.25 to 0.75 mole of these elements per mole of the hydrogenation metal is employed. Likewise, about 0.03 to 5, optimally about 0.05 to 2 and preferably about 0.1 to 1 mole of the metals such as copper, lead or mercury per mole of the hydrogenation metal is incorporated into the catalyst.

Among the benefits obtained from employing the above-mentioned balanced catalysts in the present process are the increased production of branched chain paraffins, more favorable control of catalyst activity and the simplification of catalyst reactivation techniques whereby a

readily regenerable catalyst can be employed in the process.

Turning now to the drawing, a hydrocracking feedstock such as a heavy catalytic cycle oil boiling in the range of about 550° F.-650° F. and containing substantial amounts of polycyclic aromatic hydrocarbons is passed by way of line 11 into a hydrocracking reactor 12 containing a bed of arsenided nickel on silica-alumina catalyst. The catalyst contains 5 percent nickel, 2.5 percent arsenic and the silica-alumina support contains about 25 percent Al_2O_3 . Hydrogen from line 13 is commingled with the feedstock and introduced into the reactor. Make-up hydrogen may be introduced into the system by way of line 13a. A catalytic debutanized naphtha having an ASTM distillation initial boiling point of 78° F. and an endpoint of 339° F., containing 8.8 weight percent C_4 's 34.4 weight percent C_5 's 28.1 weight percent C_6 's and 17.1 weight percent C_7 's and containing 53.5 percent olefins is introduced into the reactor through line 14. Typically, about 3 weight percent naphtha, based on total feed (about 4.4 mole percent olefins) is introduced into the reactor commingled with the feed. Conditions within the hydrocracking reactor 12 include a temperature in the range of about 500° F.-700° F., a pressure in the range of 750 to 1,500 p.s.i.g., an overall liquid hourly space velocity between about 0.5 and 5 volumes of hydrocarbon per hour per volume of catalyst. The effluent is withdrawn from the reactor 12 via line 18, cooled by passing through a heat exchanger 19 and passed by way of line 21 into a high pressure separator 22 wherein a hydrogen-rich gas is separated from the liquid hydrocrackate and passed by way of line 23 to line 13 to be recycled to the hydrocracking zone in the reactor. The hydrogen-to-hydrocarbon ratio within the reaction zone is between about 1,000 and 10,000 standard cubic feed of hydrogen per barrel of hydrocarbon. The remaining liquid hydrocrackate is then passed by way of line 24 to a separation means, such as fractionator 26, wherein it is distilled to separate out a light gaseous overhead fraction containing predominantly C_1 through C_4 hydrocarbons, a light isoparaffin-rich hydrocrackate fraction boiling in the range of C_5 to 180° F. and a heavy aromatics-rich hydrocrackate fraction boiling the range of about 180° F. and 400° F. A bottoms fraction boiling above 400° F. is withdrawn via line 27 and is recycled to the hydrocracking zone by way of line 28.

The present invention will be better understood by reference to the following examples, which illustrate the beneficial effects on the operation of a hydrocracking process obtained by the addition of small amounts of light olefins to the hydrocracking reaction zone. It is to be understood that the following examples which are given for the purpose of illustration only do not serve in any way to limit the scope of the present invention.

EXAMPLE 1

A catalyst was prepared which comprised 5 weight percent nickel and 2.5 weight percent arsenic on a silica-alumina support containing about 25 weight percent alumina. In preparing the catalyst, a commercially high alumina silica-alumina cracking catalyst was impregnated with an aqueous solution of nickel acetate. The impregnated composite was dried at about 400° F., and calcined at 1,000° F. The calcined catalyst was then impregnated with a solution of triphenyl arsine in normal heptane. The heptane was evaporated and the arsenic treated catalyst was reduced in flowing hydrogen at atmospheric pressure and about 850° F.

A light catalytic cycle oil (LCCO) was hydrodesulfurized over a cobalt-molybdena catalyst to reduce the sulfur and nitrogen to 3 p.p.m. and 9 p.p.m. respectively. The estimated molecular weight of the cycle oil was about 200.

The hydrogen-treated cycle oil, together with varying amounts of pentane-2, was hydrocracked by contacting

the hydrocarbons with the arsenided-nickel-on-silica-alumina catalyst in a reactor at 550° F., 1000 p.s.i.g., a liquid hourly space velocity of 0.5 volume of hydrocarbon per hour per volume of catalyst. Hydrogen gas was supplied to the reactor to provide a hydrogen-to-hydrocarbon ratio of 6,350 standard cubic feet of hydrogen per barrel of hydrocarbon. The results obtained from the addition of the varying amounts of olefins to the hydrocracking feedstock are shown below in Table I wherein the product analysis and percentage conversion of the feedstock are given. Also indicated are the iso to normal (*i/n*) paraffin ratios for the butane and pentane fractions of the reactor effluent.

Table I

Example No.	Wt. Percent Olefin Based on LCCO	Approx. Mole Percent Based on LCCO	<i>i/n</i> Ratio		Weight Percent Yields					Percent LCCO Converted
			C ₄	C ₅	C ₁ -C ₃	C ₄	C ₅ -180	180-400	400+	
1	0.0	0.0	3.3	6.7	2.9	8.0	2.7	28.5	57.5	42.5
2	0.45	1.3	2.0	12.3	1.7	6.6	7.5	37.8	46.2	53.8
3	0.90	2.6	1.5	8.8	1.6	5.8	8.2	40.0	44.3	55.5
4	1.35	4.0	1.4	8.9	2.0	4.9	10.3	41.0	41.0	58.5
5	1.80	5.7	1.6	6.5	1.3	5.7	6.9	35.7	49.8	49.3

EXAMPLE 2

A sulfided nickel on silica-alumina catalyst was prepared by impregnating a silica-alumina cracking catalyst (25 percent alumina) with an aqueous solution of nickel acetate. The impregnated composite was dried and calcined as described above. The final composite contained 5 weight percent nickel. Subsequently, the nickel on silica-alumina composite was sulfided by contacting it with a mixture of 92 percent hydrogen and 8 percent hydrogen sulfide at atmospheric pressure and a temperature of 750° F. A cetane feed containing 0.5 weight percent sulfur as carbon disulfide was contacted with the sulfided nickel on silica-alumina catalyst under the same conditions as described above. Varying amounts of pentane-2 were added to the feed and the results of the olefin addition are shown below in Table II.

Table II

Example No.	Wt. Percent Olefin Based on C ₁₆	Approx. Mole Percent Olefin Based on C ₁₆	C ₅ <i>i/n</i> Ratio	Weight Percent Yields					Percent Conversion of Reactant
				C ₁ -C ₃	C ₄	C ₅ -180	180-400	400+	
6	0.0	0.0	15.1	4.0	18.8	27.0	18.2	31.4	68.5
7	0.5	1.8	14.0	5.0	26.2	30.7	18.7	18.1	80.5
8	10.0	36.0	11.3	3.6	13.9	27.7	16.8	37.2	58.7

From the above examples it is seen that small amounts of light olefins added to the hydrocracking feed resulted in a surprising increase in the degree of conversion of the high boiling feed to lower boiling hydrocarbons. It is further seen that if the olefins are present in excess amounts the conversion level is not increased and in fact, may even be lowered.

From the foregoing description of the present invention various modifications in the details of the operation of the hydrocracking process will become apparent to the skilled artisan, which modifications fall within the spirit and scope of the present invention.

What is claimed is:

1. A hydrocracking process which comprises adding an olefinic hydrocarbon having from 4 to 7 hydrocarbons per molecule to a high-boiling hydrocarbon feedstock to provide said olefinic hydrocarbon in an amount in the range of from about 0.3 to 6 mole percent, based on feed, and

contacting the mixture of said olefinic hydrocarbon and said feedstock in a hydrocracking reaction zone with a hydrocracking catalyst, in the presence of a hydrogen-
affording gas at a temperature in the range of about 400° F. to about 1000° F. and a pressure in the range of about 200 to about 2,000 p.s.i.g., said catalyst comprising a metallic hydrogenation component containing a metal selected from the hydrogenation metals of Group VI and Group VIII of the Periodic Table and a solid acidic cracking component, the activities of said hydrogenation component and of said cracking component being balanced to provide a high iso-to-normal ratio in the paraffins produced.

2. The process of claim 1 wherein said catalyst further comprises a minor amount of an activity-control-affording element effective to control the activities of said hydrogenation component and said acidic component to provide a high iso-to-normal ratio in the paraffins produced.

3. A hydrocracking process which comprises adding an olefinic hydrocarbon having from 4 to 7 carbon atoms per molecule to a hydrocarbon feedstock boiling in the range of about 350° F. to about 850° F. to provide said olefinic hydrocarbon in an amount in the range of about 0.3 to 6 mole percent, based on feed, and contacting the mixture of said olefinic hydrocarbon and said feedstock in a hydrocracking reaction zone with a hydrocracking catalyst in the presence of a hydrogen-
affording gas at a temperature in the range of about 450° F. to about 750° F., a pressure in the range of about 200 to 2,000 p.s.i.g.,

a liquid hourly space velocity in the range of about 0.1 to 10 volumes of hydrocarbon per hour per volume of catalyst and a hydrogen-to-hydrocarbon ratio in the range of about 1,000 to 10,000 standard cubic feet of hydrogen per barrel of hydrocarbon, said catalyst comprising (a) a solid acidic support having substantial cracking activity, and (b) a metallic hydrogenation component comprising a metal selected from the group consisting of the hydrogenation metals of Group VI and Group VIII of the Periodic Table and a minor amount, effective to provide a high iso-to-normal ratio in the paraffins produced, of an activity-control-affording element selected from the group consisting of sulfur, lead, mercury, copper, arsenic and antimony.

4. The process of claim 3 wherein said olefinic hydrocarbon is added to said feedstock prior to its introduction into said reaction zone.

5. The process of claim 1 wherein the addition of said

olefinic hydrocarbon to said feedstock is made in said reaction zone at at least one point.

6. The process of claim 1 wherein said olefinic hydrocarbon is added to provide an amount of about 1.5 to 4 mole percent, based on said feedstock.

more percent, based on said feedstock.

7. The process of claim 3 wherein said olefinic hydrocarbon has from 5 to 6 carbon atoms per molecule.

8. The process of claim 3 wherein said feedstock is a catalytic cycle oil substantially boiling in the range of about 350° F. to about 850° F.

about 350° F. to about 850° F.

9. The process of claim 3 wherein said olefinic hydrocarbon is provided by a catalytic naphtha hydrocarbon containing substantial C₅ and C₆ olefins.

10. The process of claim 3 wherein said catalyst comprises a sulfided nickel on silica-alumina cracking support.

11. The process of claim 3 wherein said catalyst comprises an arsenidized nickel on silica-alumina cracking support.

12. The process of claim 3 wherein the addition of said

12. The process of claim 3 wherein the addition of said olefinic hydrocarbon to said feedstock is made in said reaction zone at at least one point.

Reaction zone at at least one point.

13. The process of claim 3 wherein said hydrogenation metal is a Group VIII metal and said activity-control-affording element is sulfur, said sulfur being present in an amount from about 0.1 to 1 mole per mole of said Group VIII metal.

14. The process of claim 3 wherein said hydrogenation metal is a Group VIII metal and said activity-control-affording element is arsenic, said arsenic being present in an amount from about 0.1 to 1 mole per mole of said Group VIII metal.

10 Group VIII metal.

15. The process of claim 3 wherein said olefinic hydrocarbon is added to provide an amount of 1.5 to 4 mole percent, based on said feedstock.
